UNITED STATES PATENT OFFICE.

FRANK N. WILSON, OF WEBSTER GROVES, MISSOURI.

CONVEYER.

Application filed July 7, 1922. Serial No. 573,429.

To all whom it may concern:

Be it known that I, FRANK N. WILSON, a citizen of the United States, residing at Webster Groves, in the county of St. Louis 5 and State of Missouri, have invented certain new and useful Improvements in Conveyers, of which the following is a specification.

My present invention relates to conveyers and more particularly to a conveyer chain 10 and blades carried thereby and is a distinct and practical improvement to overcome certain objections to and defects in the universal type of chain and blades in order to adapt the same to the work of conveying 15 lump coal up an incline, as set forth in my copending application, Serial No. 530,183 filed January 18, 1922, now Patent 1,467,700, September 11, 1923.

A further object of the invention is the 20 provision of a conveyer blade which is yieldable at its base to permit expansion of the blade while riding over an arc due to the connection of the blade to chain links, which are separated by a plurality of intermediate 25 links, and permit contraction of the base to normal position while travelling along a straight path.

With the above and other objects in view, the invention consists in the novel features 30 of construction more fully described and finally pointed out in the appended claims.

Referring to the accompanying drawings forming a part of this specification wherein like reference characters denote similar parts 35 throughout the several views:

Fig. 1 is a plan view of a conveyer chain and blades embodying my invention.

Fig. 2 is a sectional view of the chain sprocket.

Fig. 3 is a plan view of a combined link and blade support.

Fig. 4 is an end elevation thereof.

Fig. 5 is a fragmentary view in side elevation of a sprocket and three of the links of the chain in operative relation therewith.

Fig. 6 is a plan view of a modified form of conveyer chain blade embodying my invention.

Fig. 7 is a side elevation thereof, showing the inner chain guide and bed plate.

Referring to the drawings, the reference character 1 designates the bed plate of a conveyer device provided with the inner and outer guide members 2 and 3 which are spanned with a cover plate 4. Each of the inner and outer guide members is provided

with a vertically disposed link receiving groove 5 communicating with a central horizontally disposed link receiving groove 6, as shown more clearly by Fig. 7.

The reference character 8 indicates a special chain sprocket rotatably mounted on a stub shaft 9 which is suitably fixed to the bed plate 1. The sprocket 8 is provided with a deep peripheral groove 10 for receiving the horizontally disposed links of a chain 65 while the vertically disposed links of the chain are seated in the recesses or pockets 11 which are spaced apart by means of its opposed shoulders 12, as clearly shown in Figs. 70 2 and 5.

The endless conveyer chain which is adapted to ride over a pair of spaced sprockets 8, is a link chain and consists of ordinary elongated links 13 and the suitable spaced 75 blade supporting links 14. The blade supporting links or combined links and blade supports 14 are preferably solid and are provided with the end openings 15 for the reception of the ordinary chain links 13, as 80 clearly shown in Fig. 1. Each blade supporting link is provided with a lateral extension or ear 16 which is provided with a longitudinally directed slotted opening 17, as shown in Figs. 1 and 3.

The conveyer blades 18, which are supported by means of the links 14, each consists of the arms 19 and 20 spaced apart at their outer ends by a block 26' and fastened together by any suitable means such as a 90 rivet 26, as clearly shown in Fig. 6. Each of the arms 19 and 20 has an inner folded portion 23 arranged to form an opening for the pin 24 and fixed to the blade arms by suitable securing means, such as bolts 25. 95 At the base of each blade arm is a slotted opening 22 into which extends the ear 16 of the blade supporting link 14. The pin 24 of each blade arm passes through slots 17 in the ear 16 to connect the blade to the 100 chain and to be thereby supported. The blades 18 shown in Fig. 1 are formed of a single piece of material to provide the arms 19 and 20, instead of two pieces, as shown in Fig. 6.

The blades comprising the arms 19 and 20 being made from resilient material, such as spring steel plate, for example, it is evident that the free ends of the arms at the base 110 of the blade are free to expand or spread apart to prevent buckling of the chain, especially in moving or riding over a short

arc, as when riding over the sprocket 8. This arrangement provides a flexible or yieldable conveyer blade capable of being connected to a pair of chain links which are separated a suitable distance from each other by means of one or more intermediate ordinary chain links 13, thus eliminating the necessity of attaching the blade to a single chain link, which is not as preferable a connection as that herein disclosed.

It is evident from the foregoing description that by having the upright chain links ride in the vertical grooves of the guide members 2 and 3 there is no possible chance for the chain to buckle or establish lateral displacement from any load strain on the conveyer blades, as the upright links cannot be displaced in their grooves. The horizontal groove in the guide members receives the horizontally disposed link only and this groove prevents the links from vertical displacement only as there is no load strain, or at least very little load strain, on these links.

It is essential to remember that the arms 19 and 20 are capable of expanding or spreading apart when necessary, especially when the arms pass over the sprocket, when the distance between the blade supports is increased as compared with the distance when the blades are travelling in a rectilinear direction. It is apparent that the blades are capable of flexing and expanding at the base to relieve extraordinary stresses occasioned by loads locally excessive at any particular time. This desirable result is achieved not only by the pin and slot connection of the blades with the links but also by the inherent resiliency of the metal from which the blades are constructed.

It will be observed from Fig. 1 of the drawings that when the slotted openings 17 are employed in links 14 the tension on arms 19 and 20 has the tendency to draw the pins 24 and hold them toward each other in the openings and it will be apparent that should there be any cause for the spreading apart of the arms occasioned by load strain, slack in chain, or any other cause, the pins 24 can move in the openings 17.

While I have shown the openings 16 of the links 14 as slotted, it is apparent that the openings may be of the same size as the pins 24.

While I have shown and described the preferred embodiment of my invention, it will be apparent that certain changes may be made in the construction and arrangement of parts without departing from the invention and I do not desire to be limited to the exact structure shown except within the scope of the appended claims.

Having thus described my invention, what I claim is:

1. A conveyer chain consisting of a pair 65 of chain links each having a laterally extending lug having a slotted opening, a plurality of chain links intermediate said first mentioned links and connecting them together, spreadable V-shaped members, and means to connect said members to the slotted lugs of said first mentioned links to permit spreading of said members at the base thereof.

2. An endless conveyer having a chain 75 consisting of a series of links provided with laterally extending lugs, which lugs are each provided with a slotted opening, a plurality of links connecting said first mentioned links, and a plurality of blades connected to 80 the lugs of said first mentioned links by means of pins passing through the slotted openings.

3. In an endless conveyer, a chain consisting of a series of links having laterally 85 extending lugs, each of which lugs is provided with a slotted opening, said lugs each having a slotted opening therein, a plurality of connecting links, a plurality of blades, each blade being provided with diverging 90 arms, and means to connect the free ends of said arms to said lugs to permit movement in the openings in the lugs.

4. In an endless conveyer, a chain having links with slots therein and links 95 connecting said first mentioned links, and a plurality of blades, each blade having two arms connected together at their outer ends and having their inner ends connected to two links having slots by pins movably 100 receivable in said slots.

5. A conveyer blade for attachment to an endless conveyer chain comprising a pair of blade arms converging toward their outer ends and having their inner ends flexibly 105 spaced apart to form a substantially V-shaped conveyer blade, the inner ends of each blade arm being provided with a central longitudinally disposed cut-away portion to provide spaced bifurcated inner ends 110 for the blade arms, said bifurcated ends being folded back to engage the inner faces of the blade arms in such a manner as to provide a pair of opposed vertically disposed bearings for the bifurcated ends of 115 the blade arms between which bearings a chain lug is adapted to be pivotally connected to the blade arms, and means for fixing the folded bifurcated ends of the blade arms to the blade arms.

In testimony whereof, I have hereunto signed my name to the specification.

FRANK N. WILSON.
